MECHANICAL PENCIL

Joseph Meilner, West Orange, N. J., assignor to
Eagle Pencil Company, a corporation of Delaware

Application March 28, 1935, Serial No. 13,378

5 Claims. (Cl. 120—18)

My present invention relates to mechanical pencils, more especially to that type which operates by helical or screw feed.

As conducive to a clear understanding of the invention, it is noted that in mechanical pencils of the helical feed type it has heretofore been important to provide an accurate and correspondingly costly correlation between the slotted lead tube and the encircling helical track for the offset of the lead propeller riding in said tube. For, were the fit between said track and said tube excessively tight, the need for forceful manipulation during point adjustment would render the pencil objectionable even though the structure were sufficiently strong to withstand the strain. On the other hand, were the frictional grip between the lead tube and the barrel or track insufficient, the serious difficulty would arise that the lead point would recede into the barrel under pressure exerted in writing.

20 It is among the objects of the invention to provide a pencil of the above type that with little effort is adjustable for writing, yet without the looseness that leads to the objectionable recession of the point under writing pressure and this 25 without on the one hand complicating or adding parts to the construction, or on the other hand introducing the need and expense for operating to close tolerances.

30 In the accompanying drawing, in which is shown one of various possible embodiments of the several features of the invention:—

Fig. 1 is a view in longitudinal cross section showing the invention applied to one desirable 35 form of pencil,

Fig. 2 is a fragmentary view in longitudinal cross section taken on the line 2—2 of Fig. 1,

Figs. 3 and 4 are transverse sectional views 40 on a larger scale taken respectively on lines 3—3 and 4—4 of Fig. 1,

Fig. 5 is a perspective view from one side of the lead tube, and

Fig. 6 is a similar perspective view from the opposite side of said tube.

45 Referring now to the drawing, the barrel 10 is shown of molded composition, such as "bake-lite", vulcanite and the like with an unlined bore 11 having a threaded or helical track 12 molded as a unitary part thereof. Within the bore 11 is 50 a metal tube 13 which extends the entire length of the pencil, and accommodates a lead propeller 14 with an offset portion 15 protruding through a longitudinal slot 16 in the tube and riding along the helical track 12. Preferably the lead 55 propeller comprises a clutch tube 14 frictionally

gripping the rear end of the lead 17, and an ejector rod 18 telescoped thereinto and having an offset 19 also riding along the track 12. The ejector rod advances with the clutch tube 14 but is caused to be advanced relative thereto for ejection of the lead stump after the clutch tube has reached the point extremity of the track 12.

5 A ferrule 20 preferably is keyed at 22 to the rear end of the tube 13 and is rotatable on the upper end of the barrel 10 to rotate the tube 13 within the barrel. Preferably an eraser carrying ferrule 21 is frictionally and removably telescoped over ferrule 20. The forward or point end of the tube 13 extends into and preferably has a bearing in a depression 23 in the metal tip 25 from the point of which the forward end of the lead 17 protrudes. Tip 25 may be molded at its wider end 26 into the forward end of the molded barrel structure 10.

20 The construction thus far briefly described is substantially that of the prior patent to Chesler 1,956,271 of April 24, 1934, to which reference is made for further details, which however, are not material to the present invention. It will be understood that the improvement now to be described is by no means limited in its applicability to the specific structure of the Chesler patent illustratively described, but is likewise useful in connection with barrels of metal or with barrels having distinct helical feed sleeves or liners. The invention is also applicable in 25 relations in which the helical feed sleeve or track is rotatable with the ferrule and the slotted lead tube is fixed relative to the barrel.

30 According to the present invention the lead tube 13 may be made of a diameter slightly smaller than the bore of the barrel, so as to afford minute clearance therein. Near its upper end the lead tube is spread out to afford a resilient clutch to grip the corresponding portion of the barrel. A desirable manner of producing this clutch correlation is shown in Figs. 5 and 6, where a longitudinal slit 30 is cut into the tube diametrically opposite the slot 16 and by resort to an appropriate spreading tool the bridges of metal 31 and 32 between the slit and the slot are spread outwardly to cause the tube, slot 16 and slit 30 to be bowed as shown to a gradually widened middle or spindle shape at that localized region. In the course of insertion of tube 13 into the barrel 10, the widened spindle portion 30—32 of the tube will be somewhat contracted by the bore 11 of the barrel and will thereby be caused resiliently to clutch or grip 35 said bore near the upper or ferrule end thereof.

55

The length of tube 13 between clutch 30-32 and point 25 has slight clearance in the barrel.

By the arrangement set forth, even though the bore 11 or the tube 13 be not made with great accuracy, the spring clutch 30-32 affords a dependable hold to prevent receding of the point under writing pressure. The split tube being substantially free from contact with the bore of the barrel substantially throughout the length thereof, there is no likelihood of the parts becoming jammed and the adjustment of the lead is readily effected without distortion of the tube 13 since the readily yielding clutch 30-32 is near the ferrule 20 from which said tube is turned.

It will thus be seen that there is herein described apparatus in which the several features of this invention are embodied, which in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters Patent is:

1. A mechanical lead pencil comprising a barrel having a coaxial helical feed rigid therewith, a metal tube passing through said barrel and having a lead follower therein with a lateral offset protruding through a slot longitudinally of said tube and riding in said helical feed, a bearing for said tube near the point of said pencil, a ferrule at the opposite end of said pencil rotatable on said barrel and fixed to said tube, said tube having a portion of the continuous length thereof near said ferrule spread outward for frictional engagement with the inner cylindrical wall of the helical feed, the length of said tube between said spread portion and said point being substantially free from frictional engagement with said helical feed.

2. A mechanical pencil comprising a barrel having a helical feed rigid and coaxial therewith, a feed tube extending longitudinally through said barrel, means fixed to one end of said tube, rotatable about said barrel and serving

to rotate said feed tube, a lead propelling member within said tube having an offset protruding through a slot longitudinally thereof and riding along said helical feed, said slotted tube being also slit for a short part of the length thereof near the ferrule, the metal between the slot and the slit being spread outward to afford a friction clutch between the inner cylindrical part of the helical feed and the slotted tube. 5

3. A mechanical pencil comprising a barrel 10 having a helical feed rigid and coaxial therewith, a feed tube extending longitudinally through said barrel, rotatable means exposed at one end of said tube and connected to and serving to rotate said feed tube, a lead propelling member within 15 said tube having an offset protruding through a slot the length of the tube and riding along said helical feed, said slotted tube having a short slit longitudinally thereof along the element diametrically opposite the rear portion of the slot 20 thereof, the strips of said tube between said slit and said slot, being spread outward to afford friction clutching engagement of the tube in the helical feed, the forward end of said slotted tube having bearing engagement in the barrel near 25 the point end thereof.

4. A mechanical pencil comprising a barrel of 30 molded material having an integral helical feed track therein, a metal tube within said barrel, means attached in driving relation to said tube, and rotatable about the end of said barrel, said tube having a lead propelling member therein with a lateral offset protruding through a slot longitudinally of said tube and riding along said track, 35 said tube having one or more short longitudinal slits near the ferrule end thereof in addition to said slot, with the intervening bands of metal spread outward, frictionally to clutch the inner wall of the barrel, the forward end of said tube having a bearing mount in the barrel near the 40 point thereof, the length of said slotted tube between said clutching portion and said point being substantially free from friction engagement with respect to said barrel.

5. As an article of manufacture, a feed tube 45 for a mechanical lead pencil, said tube being of metal stock having a longitudinal slot from end to end thereof and having a short slit near the rear end thereof spaced from said longitudinal slot, the metal of said tube being spread outward 50 between said slit and said slot for a friction clutch conformation therat.

JOSEPH MEILNER.
